UNITED STATES PATENT OFFICE

2,494,430

ROTATING KITE

James R. Carnwath, Bothell, Wash.

Application March 29, 1948, Serial No. 17,680

2 Claims. (Cl. 244—153)

1

My invention relates to a new and novel form of rotor kite which is constructed in such a manner that it derives its lifting effort from the Magnus effect which may be briefly and non-technically described as follows:

A cylinder rotating in a fluid medium such as air will, due to friction, cause a film of that medium to adhere and rotate with it; therefore a horizontal cylinder rotating in an air stream in such a direction that the motion of the top side of the cylinder is in the same direction as the air stream and the bottom therefore opposite to it will cause the rotating film of air on the top side of the cylinder to move with the air stream and cause a rarefaction of the air when the peripheral speed of the cylinder is greater than the velocity of the air stream and cause a compression on the lower side thereby causing a lifting upward of the cylinder. By roughing the surface such as corrugating etc. or by substituting different shaped surfaces this effect may be increased. My kite is therefore preferably constructed of two substantially semi-circular vanes mounted parallel to each other about a common parallel axis and in such a manner that the kite will be rotated by the wind itself. The object of my kite and its construction are more fully described in the accompanying specification, shown in the drawings and finally pointed out in the appended claims.

Fig. 1 is a perspective of my kite in flight and with its string reeling mechanism.

Fig. 2 is a small perspective of one end of the kite showing a noise maker that may be attached.

Fig. 3 is a longitudinal cross section of my kite showing attachment of small generators when the kite is to be used for signalling.

Fig. 4 is a cross section taken upon the line 4—4 of Fig. 3.

Fig. 5 is a similar cross section showing another form of wing.

Fig. 6 is also a similar cross section showing another form of wing.

Fig. 7 is a fragmentary view showing how the wings may be attached to their intermediate sections.

Fig. 8 is a fragmentary view showing the method of attaching the wings to the end plates.

Fig. 9 is a fragmentary view showing a particular form of edge structure for the wings.

Fig. 10 is a partial front elevation of one end of the kite showing the stabilizing structure that may be used as part of the kite structure.

Fig. 11 is a right end view of Fig. 10.

2

Fig. 12 is a section taken upon a line 12—12 of Fig. 10.

Fig. 13 is a partial elevation similar to Fig. 10 showing the kite in a sloping position and a stabilizing mechanism coming into play to right the kite.

Fig. 14 shows a different form of stabilizing structure similar to the air foils of a plane.

Referring more particularly to the drawing: reference numeral 10 represents the kite in its entirety (Figs. 1 and 3). Reference numeral 11 indicates the vanes or wings; 12 the end plates, and 13 the intermediate sections; and 14 the shafts upon which the kite rotates.

15 Several different types of material may be used for the construction of the kite, a prerequisite of course being that the material be strong for the weight involved. Material such as balsa wood, light types of plastics, or light metal, with proper construction, or paper may be used. The presently described kite is shown made of corrugated paper with a smooth backing on one side and the corrugated face left on the other. The corrugated paper is used to increase its strength quality 20 and the corrugations when turned out will cause a greater air mass to rotate with the rotor and consequently improve the lifting effort.

The construction of the kite will be described along the preferred method of assembling. The

30 center sections 13 are cut to the profile shown in Figs. 4 and 7 which is adapted to the particular design of wings shown generally throughout the present details. The sections 13 are perforated

35 with slots as shown at 15 (Fig. 7) which are substantially segments of a circle in shape and which are provided with tabs as shown at 16. The material outside of the slots is cut as shown at

40 17. The center of segments 13 are provided with metal eyelets as shown at 18. The wings 11 are perforated as shown at 19. These perforations are located where the intermediate sections are to be placed and spaced so as to register with the tabs 16 in the slots 15. By bending the material

45 on either side of slits 17 in the manner shown at 20, the wings may be easily pushed into the slots till perforations 19 coincide with tabs 16 and pressed over them. The material now is bent

50 back to form a flat surface and a gummed sticker secured to each side of the material over the slits 17 as shown at 21 (Fig. 4). The shafts 14 are now assembled in place.

The shafts 14 are L shaped as shown in Fig. 3 consisting of the inner or shaft portion 14a and the outside portion 14b. The inner end of portion 55 14a is stamped to provide ears 14e. The outside

portion 14b is stamped to provide ears 14e. The outside

portion 14b is provided with a hole 14h. The shaft is assembled in place by threading the outside end through eyelets 18. The outside ends 12 are now assembled in place.

The outside ends 12 are preferably circular in shape and are perforated as shown at 22 to receive ears 23 at the ends of the wings. The ears 23 are slit as shown at 24. The center of ends 12 are provided with eyelets 25. The ends 12 are now slipped over the portion 14b on to the portion 14b of the shaft and threaded over the ears 23 of the wings. Fig. 8 shows the end 12 slipped over the ears 23 of one wing and the other wing as it appears just before the end has been slipped in place. After the ends are slipped in place the ears 23 projecting beyond the end plate 12 are turned outward as shown at 26. The ends 12 are now more firmly secured by gummed stickers 27 secured over the outturned ears 26, see Fig. 1.

Kites with wing shapes shown in Figs. 5 and 6 may be assembled with their center sections in substantially the same manner as previously described for wing shapes shown in Fig. 4.

A noise maker for the kite may be made as shown in Fig. 2 which consists of a Z-shaped metal plate as shown at 27 which consists of a center section and the two end sections 28 which are bent outwardly as shown. Plates 27 may be secured in place by ears stamped in the metal as shown at 29 and forced through the end plates 12 and clinched on the inside. The end sections 28 are bent out just far enough to interfere with the outer portions 14b of the shafts making a clicking noise as they spring past.

The kite is provided with two strings, one string being attached to each of the two shafts 14 by passing them through the holes 14h and tying in place. The strings may be wound on any suitable form of reel as shown in Fig. 1. This reel assembly consists of a substantial bar 30 near the center of which is placed a two section reel 31 which rotates freely about a spindle 32 the lower end of which is secured to the bar 30 and the outer end provided with a thumb nut 33. The outer ends of bar 30 are provided with screw eyes 34 through which the strings pass to keep them in the proper spaced relation. The reel is provided with a handle 35 for winding up the string in bringing the kite down.

For signaling purposes the kite may be provided with small electric generators suitably equipped with an interrupter to operate light in code as shown at 36 (Fig. 3) the fields of which are secured to the end plates 12 and the armatures secured to the portions 14a of the shafts 14. The generators would supply power to lights on the kite or to a radio transmitter or other device located on the kite or near the kite operator.

When the generators are used the kites are generally made much larger and more substantial. When the generators are used the shaft 14a is preferably made of two pieces of hollow tubing joined together at their elbow and the wires from the generators passed through the hollow shafts. A detail construction of this is not shown as it may be made in several approved methods. The generators may be made to light small lights secured to the kite string or kite as shown at 37 and at 37a (Fig. 1).

The kite may also be used for signal by attaching very light plates of metal 38 to the kite strings. These metal plates may be polished or

of different colors to convey signals or messages.

The kite may also be used for signaling by code by attaching an interrupter mechanism 36a that may be rotated with the generator to interrupt the current to the lights 37 and 37a causing them to flash in any prescribed code pattern. The interrupter 36a may be of any approved form such as a toothed disk operating a pair of contact points by changing the disks different code patterns may be transmitted.

The preferred form of stabilizing mechanism is shown in Figs. 10 to 13 respectively and is represented in its entirety by reference numeral 40.

15 In employing this type of stabilizing mechanism the shaft 14a is extended out as shown at 14c (Figs. 10-12-13). Over the outer end 14c of the shaft is first slipped a very light bracket 41 perforated at its outer end to receive the kite string.

20 After the bracket 41 is slipped in place the stabilizing mechanism 40 is next slipped in place. Stabilizing mechanism 40 consists of a tube 42 to the ends of which are secured brackets 43 and 44 to the outer ends of which in turn is secured stabilizing wing 45 (Figs. 10-11 and 13). Stabilizing mechanism is kept from sliding off the shaft 14c by means of a round point set screw 46 engaging in a small slot 47 near the end of the shaft. The outer end of the tube 42 is provided with a slot 48. Into the slot 48 is slipped the upper end of a stabilizing lever 49. The stabilizing lever 49 is provided with an eye 50 which registers with perforations 51 in the outer end of the tube 42. Passed through the perforations 51 of the tube 42 and eye 50 of the lever 49 is the end of a shaft 53. The shaft 53 is free to oscillate in perforations 51 but is rigidly secured in the eye 50 of the lever 49. The outer end of shaft 53 is bent so as to form a crank 54. The outer end of crank 54 is provided with an eye 55. Connecting with the eye 55 of the crank 54 is the eye end of the connecting rod 56. The upper end of connecting rod 56 is provided with eye which interconnects with a small eye bolt 57 which is secured to stabilizing wing 45 by means of nut 58. The lower end of stabilizing lever 49 is provided with a weight 59.

50 In Fig. 14 airfoils 60 are shown pivoted on the outer ends of shaft 14a. From the back edge of the airfoils 60 are extended struts 61 to which is attached controllable foils 62 and 63 similar to the rudder on the elevators of an airplane. In flight this kite resembles very much the appearance of an airplane.

55 Method of operations is as follows:

When the kite is pulled rapidly or set up in a breeze the air striking concaved surface of the upper wing 11 (Fig. 1) the kite will be caused to rotate in a clockwise direction which in turn will cause the kite to lift due to the so-called Magnus effect as previously described. The exterior corrugated surface will cause a greater air mass to rotate with the wings increasing the lifting effort. The rotation of the wings with its end pieces will cause the generators to rotate with it producing a current which may be used to light the lights or to operate a small radio set attached to the kite if desired.

60 The stabilizing effect of the stabilizers at each end of the kite one of which is shown in Figs. 10 to 13 is as follows: Suppose the right hand end of the kite tilts downward as shown in Fig. 13 the lever 49 with its weight 59 will act as a pendulum causing the crank 54 to turn downward

with respect to the tube 42, pulling the connecting rod 56 with it causing the back edge of stabilizer wing 45 to rock downward and the front edge up, permitting the oncoming air stream to strike the under surface of stabilizer wing 45 producing an upward lift. When the kite has again reached the horizontal position stabilizer wings 45 will again be horizontal or slightly drooping to provide additional lift. If the kite tilts in the opposite direction to that just described it is self evident that the back edge of stabilizer wing 45 will be rocked upward and the front edge downward permitting the oncoming air stream to strike the top surface of stabilizer wing 45 tending to force the end of the kite downward.

From the above description it is apparent that the lower end of a tilting kite will be lifted up by its stabilizer wing and that simultaneously the opposite or upper end of the kite will be forced downward.

I claim:

1. A rotating kite consisting of a wing, reinforcing means therefor, plates attached to either end of said wing, apertures in said plates, a rod between said plates, rotatably mounted, a portion of said rod extending beyond said wings at either end and passing through the apertures in said plates, the outer portion of said rod being bent back substantially at right angles, bearings therefor, tabs disposed upon the outer surfaces on the said end plates, flight control lines, connecting with the said rod, means for controlling the length of said flying lines and accommodating that portion of said lines which is not disposed between said control means and the kite when the latter is in flight.

2. In a device such as is described a wing consisting of two complementary horizontal mem-

bers, substantially semi-cylindrical in form, the outer surfaces of which are roughened, a plate at either end of said member, apertures therein, and tabs disposed thereupon, a rod extending along said wing and beyond the same through the apertures in said end plates, the extended portion of said rod being bent back upon itself substantially at right angles, strengthening and form maintaining ribs for the complementary portions of said wing, bearings in said end plates for said rod extending therethrough, means for rotatably affixing said rod within said wing, means for controlling the kite in flight connected with said bent rods without said end plates, means for controlling the flight of said kite and its elevation while in flight.

JAMES R. CARNWATH.
